The ornamental design for a transparent oil monitoring and maintenance cover.

DESCRIPTION

FIG. 1 is a top perspective view of a transparent oil monitoring and maintenance cover showing my new design;

FIG. 2 is a bottom perspective view thereof;

FIG. 3 is a front elevation view thereof;

FIG. 4 is a rear elevation view thereof;

FIG. 5 is a left side elevation view thereof, the right side elevation view being the mirror image thereof;

FIG. 6 is a top plan view thereof;

FIG. 7 is a bottom plan view thereof;

FIG. 8 is a top perspective view of an alternate embodiment of a transparent oil monitoring and maintenance cover showing my new design;

FIG. 9 is a bottom perspective view thereof;

FIG. 10 is a front elevation view thereof;

FIG. 11 is a rear elevation view thereof;

FIG. 12 is a left side elevation view thereof, the right side elevation view being the mirror image thereof;

FIG. 13 is a top plan view thereof; and,

FIG. 14 is a bottom plan view thereof.

The broken lines in the drawings depict unclaimed environmental subject matter.
